EDMUND E. HANS, OF DETROIT, MICHIGAN.

PURIFIER FOR LUBRICATING OILS.

1,420,837.

Specification of Letters Patent. Patented June 27, 1922.

Application filed September 7, 1920. Serial No. 408,684.

To all whom it may concern:

Be it known that I, EDMUND E. HANS, a citizen of the United States, and residing at Detroit, in the county of Wayne and State 5 of Michigan, have invented a new and Improved Purifier for Lubricating Oils, of which the following is a specification.

This invention relates to means for continually removing the gasoline and kerosene 10 from the lubricating oils in the crank cases of internal combustion engines so that such oil may always have its full lubricating qualities, and it is embodied in a heating vessel connected to the exhaust manifold of 15 the engine and provided with a passage through which a current of air may flow to carry away the vapors of the gasoline and kerosene, of means to lift the lubricating oil from the crank case to the heating vessel, and a conductor to carry the lubricating 20 oil from the vessel to the crank case, means being provided to cool the oil after it leaves the heating vessel.

In the accompanying drawing, Fig. 1 is a 25 side elevation of an internal combustion engine equipped with my improved lubricant purifier. Fig. 2 is a transverse section on the line 2—2 of Fig. 3. Fig. 3 is a section on the line 3—3 of Fig. 2. Fig. 4 is a view 30 showing a control valve. Fig. 5 is a section of a modified form of purifier. Fig. 6 is a view of a thermostat adapted for use with this purifier.

Similar reference characters refer to like 35 parts throughout the several views.

In many internal combustion engines having vertical cylinders drops of gasoline or kerosene of the fuel enter the crank case and mix with the lubricant therein. In such 40 engines, particularly when cold, small particles of these light fuels condense on the walls of the cylinders during the charging strokes and pass down between the pistons and the cylinder walls into the crank case, 45 where they slowly accumulate and reduce the lubricating quality of the oil therein.

The engine shown in the drawing has a crank case 1, a cylinder block 2, exhaust manifold 3, radiator 4, fan 5 and its belt 6, 50 magneto 7 and its shaft 8, and any desired driving mechanism for the magneto shaft enclosed in the case 9. These several parts have been shown conventionally as by themselves they form no part of my invention.

55 Mounted at any convenient point and driven by any convenient mechanism is an

oil pump, in the present case a rotary pump 10 mounted on the magneto shaft 8. Its suction pipe 12 extends to a low point in the crank case and it normally delivers the lubricating oil to the pressure filter 13, which may be of any desired construction, through the pipe 15. From the filter the fuel passes to the crank case, a breather pipe 14 on the crank case being shown as a convenient 60 point of attachment. The delivery pipe 15 from the pump branches, one branch 16 going to the filter and the other branch 17 to the purifier 18, a small needle valve 19 being shown as controlling the flow to this 70 purifier.

Connected to the exhaust manifold 3 is a chamber 20, preferably integral with the exhaust manifold, having a removable top 21 provided with holes 22 which lead into 75 the pipe 23. This pipe has a funnel 24 at one end turned toward the fan 5 and may have a down-turned rear end 25. A pipe 26 connects into the chamber 20 at about the desired liquid level to carry off 80 the purified lubricant, while the branch 17 from the pump 10 connects to the chamber 20 near its bottom.

The pump 10 forces lubricating oil 85 through the filter 13 under more pressure than is necessary to lift the oil to the purifier 18, and the flow to the purifier will therefore be continuous so long as the pump is operating. The needle valve 19 regulates this flow so that the oil which does pass will 90 be heated to a sufficiently high temperature to evaporate the gasoline and kerosene. The vapors of these hydrocarbons rise and pass out through the small passages 22 into the pipe 23 and are carried along by the air 95 which enters the funnel 24, passing down and rearwardly below the floor of the vehicle.

Lubricating oil is less effective when hot and some means should be provided to reduce its temperature after leaving the purifier. I have shown a number of fins 28 mounted on the pipe 26 which fins will radiate the heat of the lubricant. The filter 13 is also provided with fins for the same 100 purpose and it will be observed that the suction pipe 12 of the pump 10 connects to the crank case and to the pipe 26 so that all the oil from this pipe 26 will be taken up by the pipe 12.

I have also shown in dotted lines a pipe 29 leading from the purifier down through

60

75

110

the radiator to be used in place of the pipe 26, or in addition thereto, and this pipe will always carry cold oil to the crank case.

In cold weather the oil becomes thick and may not flow freely down the pipe 26 and may even fill the purifier and escape through the passages 22. To avoid this I may employ a thermostat 30 secured at its ends to the lugs 31 at the ends of the heating chamber 20 and connecting to the valve 32 by means of the rod 33. Brass will preferably be the upper metal and steel the lower so that the valve 32 will be held down to close the upper end of the pipe 17 until the liquid in the chamber 20 reaches the desired temperature. With increasing temperatures the valve rises so that constantly increasing volumes of oil will enter the purifier until it reaches a maximum determined by the needle valve 19.

It is evident that the details of construction of this device may all be changed without departing from the spirit of invention set forth in the following claims. This Fig. 5 shows a purifier 34 attached to a vertical exhaust pipe 35, the oil entering at 36 and flowing out at 37 and the hydrocarbon vapors passing out through the opening 38.

I claim:

30 1. A purifier for the lubricating oil of internal combustion engines consisting of a heating chamber attached to the exhaust passage of the engine, means to cause a flow of lubricant through the chamber, an air 35 passage across the top of the chamber and connecting thereto by holes in the dividing wall, and means to cause a current of air to pass through the passage.

2. A purifier for the lubricating oil of internal combustion engines consisting of a heating chamber attached to the exhaust passage of the engine, means to cause a flow of lubricant through the chamber, an air 45 passage across the top of the chamber and connecting thereto by holes in the dividing wall, means to cause a current of air to pass through the passage, and means controlled by the temperature of the lubricant in the heating chamber to resist the flow of lubricant.

50 3. A purifier for the lubricating oil of internal combustion engines consisting of a heating chamber formed integral with the exhaust pipe of the engine, a cap for said chamber, an air pipe attached to said cap, said pipe and cap being formed with registering holes, a funnel at one end of said pipe, a fan to force air through the pipe, and means to conduct lubricant to and from the heating chamber.

4. A purifier for the lubricating oil of internal combustion engines consisting of a heating chamber attached to the exhaust passage of the engine, means to cause lubricant to flow from the crank case to said

chamber, means to cool the lubricant after it leaves the chamber, said chamber having openings to permit the escape of volatile matter, an air passage into which said openings extend, and a fan to cause a current of air through the passage.

5. A purifier for the lubricating oil of internal combustion engines consisting of a heating chamber attached to the exhaust passage of the engine, means to cause lubricant to flow from the crank case to said chamber, means to cool the lubricant after it leaves the chamber, said chamber having openings to permit the escape of volatile matter, a valve to control the flow of lubricant into said chamber, and a thermostat in said chamber operated by the temperature of oil to control the valve and flow of the lubricant.

6. A purifier for the lubricating oil of internal combustion engines consisting of a heating chamber attached to the exhaust passage of the engine, a pump to cause lubricant to flow from the crank case to said chamber, a suction pipe for the pump connecting to the crank case below the oil level therein, a discharge pipe for said pump connecting to the heating chamber, and an overflow pipe extending from the heating chamber to the suction pipe of the pump.

7. A purifier for the lubricating oil of internal combustion engines consisting of a heating chamber attached to the exhaust passage of the engine, a pump to cause lubricant to flow from the crank case to said chamber, a suction pipe for the pump connecting to the crank case below the oil level therein, a discharge pipe for said pump connecting to the heating chamber, an overflow pipe extending from the heating chamber to the suction pipe of the pump, and means to cool the heated lubricant.

8. A purifier for the lubricating oil of an internal combustion engine consisting of a heating chamber having a volatile gas outlet, means for heating said chamber, means to cause lubricant to flow from said engine to said heating chamber, means to regulate the flow of the lubricant into said heating chamber, and means actuated by the temperature of the lubricant for controlling the means regulating the flow of the lubricant into said heating chamber.

9. A purifier for the lubricating oil of an internal combustion engine consisting of a heating chamber having a volatile gas outlet, means for heating said chamber, means to cause lubricant to flow from said engine to said heating chamber, and a thermostat for controlling the flow of lubricant into said heating chamber.

10. A purifier for the lubricating oil of an internal combustion engine consisting of a heating chamber having a volatile gas outlet, means for heating said chamber, means

to cause lubricant to flow from said engine to said heating chamber, a thermostat for controlling the flow of lubricant into said heating chamber, and means to cool said heated lubricant and return said cooled lubricant to the engine.

- 5 11. A purifier for the lubricating oil of an internal combustion engine consisting of a heating chamber having a volatile gas outlet, means for heating said chamber, a cooler, means to cause lubricant to flow from said engine to said heating chamber and cooler simultaneously and said lubricant passing through the cooler is returned to the engine.
- 10 12. A purifier for the lubricating oil of an internal combustion engine consisting of a heating chamber having a volatile gas outlet, means for heating said chamber, a cooler,
- 15

means to cause lubricant to flow from said engine to said heating chamber and cooler simultaneously and said lubricant passing through the cooler is returned to the engine, and the lubricant passing through the heating chamber and freed of volatile gases is returned to mix with the lubricant flowing from said engine simultaneously to the cooler and heater.

13. In a purifier for the lubricating oil of an internal combustion engine, the combination of a chamber to receive the oil, means for heating the oil in the chamber, means for causing the oil to flow from the engine to the heating chamber, and a thermostat controlled by the heated oil to regulate the flow of the oil.

EDMUND E. HANS.
